UNITED STATES PATENT OFFICE.

JOSEPH A. D'ELIA, OF BRIDGEPORT, CONNECTICUT.

OIL BURNER.

Application filed March 18, 1926. Serial No. 95,641.

This invention relates to new and useful improvements in liquid fuel burners which utilize liquid fuel as a heating medium and which fluid is volatilized and converted into a gas by being forced through the burner, including a heating retort.

The burner is of such a type that the liquid fuel supplied thereto may be fed by gravity or preferably force feeding means, and therefore by the liquid fuel become vaporized in transit to the jet orifices so that from the orifices a jet of high velocity vapor is discharged and mixed with air so that a large hot, white flame is produced.

The invention has for its general object to improve the general construction and operation of devices of this character so as to be reliable and efficient in use, to provide a burner which will be comparatively simple and inexpensive to manufacture and so designed as to enable the burner orifices to be easily and quickly cleaned, and particularly to provide a burner whereby the greatest amount of heat possible is obtained from a given amount of fuel.

With these and other objects in view the invention resides and consists in the construction and novel combination and arrangements of parts hereinafter more fully described, illustrated in the accompanying drawings, and pointed out in the claim here-to appended, it being understood that various changes in the form, proportion, size and minor details of construction within the scope of the claim may be resorted to without departure from the spirit or sacrificing any of the advantages of the invention.

Similar characters of reference denote like or corresponding parts throughout the several figures of the accompanying drawing forming a part of this specification, and upon which,

Fig. 1 shows a sectional plan view of a steam boiler to which my improved burner is shown applied, and

Fig. 2 is a side view of the burner shown in Fig. 1.

Referring in detail to the characters of reference marked upon the drawings, 5 represents the base of a heater, 6 the water chamber, 7 a combustion chamber in which the burner, again to be referred to, is positioned. 8 indicates an opening into the combustion chamber, and 9 a door for normally closing the same. 10 indicates a return pipe from

radiators, not shown, and connected to the lower portion of the boiler.

The burner, as before suggested, is preferably provided with forced draft means in the form of a motor, indicated as 11, and a pump 12 connected with and operated by the motor, said pump being positioned intermediate of the fuel supply pipe 13. This pipe obviously is connected with a fuel tank, preferably located at an elevation with respect to the burner. In some installations it is possible to place the fuel tank high above the burner and therefrom sufficient pressure may be obtained to insure a proper feeding of the oil without the necessity of the pump, but since it is not always practical to place the tank in this preferred raised position an electrically operated pump may be provided in the service pipe to insure the forced feed if it is desired. Within the pipe line 13 I provide a shut-off valve 14 whereby the liquid fuel supply from the tank, not shown, is controlled. 15 indicates a check valve which is positioned in the pipe line adjacent to the shut-off, 14, before mentioned for the obvious purpose of permitting the liquid fuel to be fed to the burner and to prevent the fuel and gas to re-act in any way upon the fuel supply. A regulation valve 16 is next provided in the pipe line, this may be of any preferred design, such as the needle valve 16 represented in the drawing, and is provided with lever connections 17 so as to be operatable from a thermostat or other heat regulating means, not shown.

From this valve the liquid fuel supply is led to the burner through a substantially horizontal pipe 18, passing through the opening 19 and door 20. This pipe may be connected with the upper part of and form an integral part of the coil 21, that is positioned above and surrounding the burner plate 22. The lowermost part of this coil extends out beyond the other parts of the coil and is carried upward where it is connected with a horizontally arranged enlarged tubular member 23 that is disposed partly across the top of the coil and over the burner and the flame arising therefrom, thereby forming a retort 23 in which the heated liquid fuel is finally transformed into a gas or vapor preparatory to its passage to the burner proper. The opposite end of this retort is connected by vertically and horizontally disposed piping 24 which forms a trap 25 and through which the

gas is passed en route to the burner plate 22. The purpose of the trap is to prevent the over-flowing of oil in case the fire should be put out and the shut-off valve 14 not closed. This 5 plate is hollow and connected by an inlet pipe 26 upon one side and a blowout pipe 27 on the other, and is further provided with a series of a suitable number of holes in its top side to constitute the jet orifices where the escap- 10 ing gas is consumed. The blowout pipe 27 is provided with a valve 28 which is normally kept closed, but which may be opened from time to time as the case may require in order to blow out any sediment which may ac- 15 cumulate in the burner. The burner is adapted to be placed in almost any kind of the commercial designs of furnaces such as are used for house heating, and is prefer- ably placed above the grates and supported 20 by fire bricks 29 or other suitable means, as is suggested by the illustration shown in Fig. 2.

Having thus described my invention what I claim is new and desire to secure by Letters Patent is:—

25 A burner comprising a coil, a liquid fuel supply pipe connected with its upper portion, valves in said pipe line to control the supply of liquid fuel, means for providing a forced feed of the fuel through the feed pipe, a relatively large heat retort disposed across the top of the coil in the path of the flame from the jet orifices of a burner, the inlet end portion of said retort being connected with the lowermost part of the coil, a trap connected with the discharge end portion of said retort, 30 a burner positioned below and central of the coil, a pipe connecting said trap and burner to supply fuel thereto, and a blow-out pipe directly connected with the burner.

35 Signed at Bridgeport, in the county of Fairfield and State of Connecticut, this 16th day of March, A. D. 1926.

40 JOSEPH A. D'ELIA.
